Patented Sept. 18, 1917.

UNITED STATES PATENT OFFICE.

CLEMENT R. UHL, OF TOLEDO, OHIO.

ARTICLE OF FURNITURE.

1,240,390.

Specification of Letters Patent. Patented Sept. 18, 1917.

Application filed November 3, 1916. Serial No. 129,295.

To all whom it may concern:

Be it known that I, CLEMENT R. UHL, a citizen of the United States, and a resident of Toledo, in the county of Lucas and State 5 of Ohio, have invented a certain new and useful Article of Furniture; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to articles of furniture, and particularly to furniture of the knock-down type.

The object of my invention is the provision of an improved article of furniture, 20 such for instance as a table, which is strong, durable and inexpensive in its construction and capable of being easily and quickly knocked down or set up, and also of being lengthened or shortened as occasion may require. Other objects and advantages of the 25 invention will be apparent from the following detailed description thereof.

While the invention, in its broader aspect, is capable of embodiment in numerous 30 forms, a preferred embodiment thereof is illustrated in the accompanying drawings, in which—

Figure 1 is a perspective view of a table embodying the invention. Fig. 2 is a perspective view of a portion of one of the table legs with the rail engaging arms attached thereto. Fig. 3 is an enlarged perspective view of one of the table rails with a part broken away. Fig. 4 is an enlarged section 35 of the upper portion of the table with parts broken away and with parts removed. Fig. 40 5 is an enlarged perspective view taken near the line 5—5 in Fig. 4, and Fig. 6 is a cross-section on the line 6—6 in Fig. 4.

45 Referring to the drawings, 1 designates each of the several legs of a table, and 2 the top thereof. Each leg 1, in the present instance, is formed of sheet metal and is 50 rectangular in cross-section with the side edges of the sheet metal meeting at a corner thereof and terminating in inwardly turned flanges 3, which are rigidly joined together by a U-shaped uniting strip 4, that is prefer-

ably spot welded thereto at spaced points, as at 5.

Projecting transversely from the upper end of each leg is a pair of arms 6, 6, which, if the leg is disposed at a corner of the table, project at right angles to each other, as best shown in Fig. 2. The arms 6, 6 are L-shaped 60 in cross-section and preferably comprise a single length of angle-iron with a portion of the top flange thereof cut away at the center to permit the other flange to be bent to fit around the outer side of the leg to which it 65 is attached, being preferably spot welded thereto, as at 7. The top flange of the bar forming the arm 6 preferably rests on the upper end of the leg and is provided at each 70 end of its cut-away portion with an integral tongue 8, which is bent into the upper end of the leg and preferably spot welded to the inner side of the sheet metal forming the leg, as shown in Fig. 2.

The aligned arms 6 of successive legs are 75 connected by side rails 9, which may be of sectional form if the space between the legs is of too great a length for a single piece rail. The rails 9 are formed of sheet metal and are triangular in cross-section, having a 80 horizontal side 10, an outer vertical side 11, and an inner diagonally disposed side 12 connecting the lower edge of the vertical side to the inner free edge of the horizontal side. The edges of the sheet forming the 85 rail meet at the upper inner edge of the rail and are secured together preferably by spot welding in a manner to form the inwardly projecting flange 13. The table top 2 is intended to rest on the top side 10 of each rail 90 and is secured thereto by screws 14 (Fig. 4), which are screwed into the table top through openings 15 in the rail flanges 13.

The leg arms 6 are intended to be inserted into the adjacent ends of respective 95 rails 9 with the flanges thereof fitting the angle formed by the rail sides 10 and 11. The rails are firmly secured to the arms by set screws 16, which project through the inner rail sides 12 in position for their inner 100 ends to seat in the angle of the respective arms 6 and exert a diagonal thrust thereagainst to retain said arms firmly seated in the outer top angle of the rails. The screws 16, instead of being threaded through the 105 sides 12 of the rails, are threaded through

5 nuts 17 carried by plates 18, which are inserted into the rails and bear outwardly against the sides 12 thereof. Each nut 17, in the present instance, is secured to the plates 18 by a retaining cage 19, which is fixed to the inner side of the plate, as best shown in Fig. 3. It is evident that when the arms 6 are inserted within and clamped to the rail sections by the screws 16, the legs are rigidly connected and the whole forms a firm and rigid support for the table top.

10 Should the space between the legs be too great for a single-piece rail 9, the rail may be spliced by inserting one or more separate rail lengths therein and connecting the adjacent ends of said lengths by a coupling bar 20, which comprises a length of angle-iron adapted to fit into the respective ends of the rail sections in the same manner that the 15 arms 6 are inserted therein, and to be secured in position by set screws 16, as described in connection with the securing of the arms 6 to the rail ends. The nuts through which the screws thread are also carried by a removable plate 18, which is inserted into the adjacent rail section ends in spanning relation to the joint, as shown in Fig. 4.

15 It is evident that a table embodying my invention may be enlarged or reduced in width or length as desired by merely substituting rail sections of different lengths for the sections in use, or using several rail sections where desired, and changing the table top to conform to the size of the table desired. It is also evident that a table embodying my invention is capable of being easily and quickly set up or knocked down and of being compactly packed for storage or shipment.

20 I wish it understood that my invention is not limited to any specific construction, arrangement or form of the parts, as it is capable of numerous modifications without departing from the spirit of the claims.

25 Having thus described my invention, what I claim as new, and desire to secure by Letters Patent, is—

1. In an article of furniture, a pair of legs each having an arm projecting therefrom toward the other leg, said arm being angled in cross-section, a rail bar having recesses in its ends adapted to receive said arms, said rail bar being angled in cross-section to conform to the angle of said arms 30 and extending at its ends adjacent to each leg, and means carried by said bar and operable to releasably secure the arms and bar together in rigid relation.

2. In an article of furniture, a leg, an arm 35 projecting transversely from said leg and angled in cross-section to form a vertical flange and an inwardly projecting flange at the upper end thereof, a rail bar having a socket in an end thereof with the outer wall 40 of said socket angled in cross-section to con-

form to the angle of said arm, and a set screw projected through the inner wall of said socket and adapted to engage said arm in the angle thereof and hold it firmly seated in the angle of said socket.

3. In an article of furniture, a leg, an arm projecting transversely from said leg, a rail bar having a socket in an end thereof for receiving said arm, a plate inserted in said socket and having a threaded part, and a screw inserted through one wall of said socket and the threaded part of said plate and adapted to engage and firmly hold the arm transversely seated in said socket.

4. In an article of furniture, a leg, an arm 45 projecting transversely from said leg and being angled in cross-section to form a vertical flange and an inwardly projecting flange, a metal rail bar of triangular form in cross-section adapted to receive said arm 50 in one end thereof, and means carried by the bar for releasably holding the arm transversely seated in an angle of said bar.

5. In an article of furniture, a leg, a metallic arm projecting transversely from said 55 leg and being angled in cross-section, a hollow metal rail bar for receiving said arm in an end thereof and having two adjoining sides conforming in angle to the angle of said arm whereby one may transversely seat 60 in the other and having a side opposed to the angle of said adjoining sides, and means carried by said opposing side and operable to releasably engage the arm and firmly hold it transversely seated within the corresponding angle of the rail bar.

6. In an article of furniture, a pair of legs, an arm projecting transversely from each leg and angled in cross-section, a hollow rail bar having two adjoining sides angled to conform to the angle of said arms 65 to permit a seating of one in the other and having a side opposed to the angle of said adjoining sides, plates secured in said bar and having threaded parts, said plates bearing outward against the side of the bar which opposes the said angle thereof, and screws projected through said last mentioned bar side and the threaded parts of said plates and bearing against the respective arms in the angle thereof to firmly retain said arms seated in the bar angle.

7. In an article of furniture, a rail bar comprising a plurality of longitudinally aligned sections having sockets in the adjacent ends thereof, a coupling bar inserted at its ends into each of said sockets and adapted to transversely seat therein, and means carried by the rail sections and operable to releasably retain the coupling bar 70 transversely seated in the section sockets and to coöperate with the coupling bar to firmly connect said sections.

8. In an article of furniture, a rail bar comprising a plurality of hollow longitu- 75

dinally alined sections, each section being formed of metal and triangular in cross-section, a coupling bar inserted into adjoining ends of said rail sections, said bar being angled in cross-section and transversely seating in an angle of each of said rail sections, and means carried by a side of the rail sec-

tions and coöperating with the other sides to releasably hold the coupling bar rigidly seated in said sections.

In testimony whereof I have hereunto signed my name to this specification.

CLEMENT R. UHL.
